SOCKET CORE FOR PIPE MOLDS

Filed Sept. 6, 1924

3 Sheets-Sheet 3

UNITED STATES PATENT OFFICE.

EDWARD HERING, OF BEVERLY, NEW JERSEY, ASSIGNOR TO UNITED STATES CAST IRON PIPE & FOUNDRY COMPANY, OF BURLINGTON, NEW JERSEY, A CORPORATION OF NEW JERSEY.

SOCKET CORE FOR PIPE MOLDS.

Application filed September 6, 1924. Serial No. 736,221.

My invention relates to socket cores for pipe molds and is particularly designed for use in connection with centrifugal molds, although obviously adaptable for other uses.

10 The object of my invention is to provide a segmental socket core which can be assembled in the mold and after the pipe is cast withdrawn from the mold without injury to the segments of the core.

15 The nature of my invention in the best form I have contemplated applying it in use will be understood as described in connection with the drawings, in which—

Figure 1 is an end view of a pipe mold 20 with my socket core secured in the bell end of the mold in the central position and ready for use in casting.

Figure 2 is a sectional view on the line 2—2 of Fig. 1.

25 Figure 3 is a similar sectional view showing two positively located segments rotated out of the mold.

Figure 4 is a cross section on the line 4—4 of Fig. 1.

30 Figure 5, a similar cross section showing two of the segments rotated out of the mold and a third segment as shifted in the mold preparatory to rotating it out of the mold.

Figure 6 is a sectional view taken as on 35 the line 6—6 of Fig. 1.

Figure 7, a similar view showing the position of the parts when the arm F is rotated to the position shown in Fig. 3, and

35 Figure 8 is a cross sectional view on the line 8—8 of Fig. 1.

A indicates the centrifugal pipe mold having a bell end A' and a flanged terminal A², A³ indicating a circular seat formed at the outer end of the bell. B is an annular ring detachably secured to the flanged end of the mold as by fastenings indicated at D, having as shown two outwardly extending arms indicated at B'. From the face of the ring and its arms B' extend the lugs C, C, and C', C', which support the pivot pins to be described. E, E, and E', E', are the four segments making up when assembled together a socket core, e and e' indicating the abutting ends of the segments and the 45 small segments E being so shaped that their ends e diverge inwardly from each other, while the wider segments E' are, of course, shaped so that their ends will fit against the ends of the segments E. The segments E

and E' are carried on arms F and F', the arms F being pivoted on the lugs C, C, by means of pins G' having squared portions G, with which the arms F engage. The portion of the pin G' which fits in one of the sockets C has a detent depression G² formed in it and on the lug is secured a latch pin H' held in a spring box H and formed with a shoulder H² by means of which and a spring H³ the spring is pressed inward so that, when the pin G' is rotated 55 to bring the socket G² into registry with the pin H', the parts will be locked together.

The arms F' supporting the segments E' are formed with slots F² at their outer ends and with shoulders F³ and F⁴ lying on each side of the slots F². These arms are pivotally supported on the lugs C' but are not directly engaged with the pins g', g, which extend between the lugs C' and the squared portions of which are fitted with bushings indicated at I and I'. The squared portions g do, however, positively engage with cams J, J; locking pins H' are provided for the pins g' as in the first described construction.

L indicates the bell end of the cast pipe.

In operation, the segments are assembled in the end of the mold to form a socket core, as shown in Figs. 1 and 2, and the casting L formed in the mold. After the casting is 65 formed, one of the shorter segments E, and afterward the other shorter segment, is rotated outward from a position shown in Fig. 3, and these segments are locked in their upward position by the latched pins H', as shown.

The wider segments E' can be rotated out of the mold in the same way and it is necessary to first shift them inward and this is accomplished by rotating the pins g' and after them the cams J, J, the cam turning 75 from the position shown in Fig. 4 to the position shown in Fig. 5, in which last mentioned position it will be seen that the cam contacts with the stop lugs F³ and F⁴ so that on the further rotation of the pin g' the segment E', which by the cam action has been forced to the position shown at the right hand of Fig. 5, can be rotated out of the mold to the position shown at the left hand side of Fig. 5, and located in this outer position by the latch pin H'. The segments having been removed from the mold, the casting can be withdrawn after which the

segments are rotated back into the mold to re-assemble them preparatory to another casting.

It will be seen that in my construction 5 all of the segments and the mechanism having to do with their movements are removably attached to the end of the mold through the annular ring B.

Having now described my invention, what 10 I claim as new and desire to secure by Letters Patent, is:—

1. A socket core for pipe molds comprising 15 multiple segments adapted when fitted together to form an annular, collapsible socket core, the abutting ends of the segments being shaped as described to permit the segments to be separably moved inward and outward to disengage them from the casting in combination with segment supporting 20 arms pivotally connected to the end of a pipe mold and means for rotating said arms to disengage the segments from the casting.

2. A socket core for pipe molds comprising 25 multiple segments adapted when fitted together to form an annular collapsible socket core, the abutting ends of the segments being shaped as described to permit the segments to be separably moved inward and outward to disengage them from the casting in combination with segment supporting 30 arms pivotally connected to the end of a pipe mold, means for rotating said arms to disengage the segments from the casting and means for locking said arms in disengaged position.

3. A socket core for pipe molds comprising 35 multiple segments adapted when fitted together to form an annular collapsible socket core, the abutting ends of the segments being shaped as described to permit the segments to be separably moved inward and outward to disengage them from the casting in combination with segment supporting 40 arms pivotally connected to the end of a pipe mold, means for shifting the arms

carrying the wider segments laterally to clear the supported segments from the casting and means for rotating the arms on their pivots to withdraw the segments from the casting. 50

4. A socket core for pipe molds comprising 55 multiple segments adapted when fitted together to form an annular, collapsible socket core, the abutting ends of the segments being shaped as described to permit the segments to be separately moved inward and outward to disengage them from the casting in combination with segment supporting 60 arms pivotally connected to the end of a pipe mold, the pivotal connection of the arms carrying the segments which are wider on their inner faces being such as will permit a lateral movement of the arms towards and away from the center of the mold, 65 means for rotating the arms to withdraw the segments from the casting, said means including cams acting on the laterally movable arms to move them inward before the arms are rotated. 70

5. A socket core for pipe molds comprising 75 multiple segments adapted when fitted together to form an annular, collapsible socket core, the abutting ends of the segments being shaped as described to permit the segments to be separately moved inward and outward to disengage them from the casting in combination with a ring attachable to the end of a mold, rotatable studs supported on 80 said ring, cams secured to the studs which support arms carrying segments of larger internal width, segment supporting arms carrying segments of less internal width secured to rotatable studs, segment supporting arms carrying segments of greater internal width pivoted on cam carrying studs by means of slots and cam contacting faces on said arms whereby when their studs are rotated the arms are first moved inward and then rotated with their studs. 85

EDWARD HERING.
